UNITED STATES PATENT OFFICE.

JAY H. HALL, OF CLEVELAND, OHIO, ASSIGNOR TO THE ELECTRIC CONTROLLER AND MANUFACTURING COMPANY, OF CLEVELAND, OHIO, A CORPORATION OF OHIO.

MOTOR-CONTROL SYSTEM.

1,122,744.

Specification of Letters Patent.

Patented Dec. 29, 1914.

Application filed September 5, 1913. Serial No. 788,280.

To all whom it may concern:

Be it known that I, JAY H. HALL, a citizen of the United States, residing at Cleveland, in the county of Cuyahoga and State 5 of Ohio, have invented new and useful Improvements in Motor-Control Systems, of which the following is a specification.

My invention relates to motor-control systems, particularly to systems in which the 10 control of an electric motor is effected partially by a manually operated controller and partially by automatic means.

More particularly, it relates to such a system in which magnetically-operated 15 switches are used for removing the resistance from the motor circuit controlling the acceleration of the motor.

One of the objects of my invention is to maintain at will the maximum resistance in 20 the motor circuit and to set in operation the successive closure of a series of magnetically-operated switches for automatically removing the resistance from the motor circuit.

25 A further object of my invention is to enable the operator to open the switches, and insert the resistance in the motor circuit at a time when no current goes through their contacts, thus preventing the formation of 30 serious arcing at the switch contacts.

Other objects and advantages of my invention will be hereinafter described.

In the accompanying sheet of drawings, Figure 1 is a diagrammatic representation 35 of a motor control system embodying my invention. Fig. 2 is a modification showing another form which my invention may assume.

Referring to the drawings, the motor to 40 be controlled is shown with the armature A and the series field winding F. The resistances for controlling the motor circuit are indicated at R', R², and R³. The resistances are arranged to be automatically controlled 45 by means of the switches S', S², and S³, these switches having operating windings C', C², and C³ arranged to be connected in the motor circuit. I prefer to use for these switches the type of switch disclosed in 50 Eastwood's Patent, No. 1,040,292, which has the peculiar characteristic of remaining open when the current in its operating winding exceeds a certain value, and operates to close the switch contacts when the 55 current is reduced. The operator's switch

is shown at M in Fig. 1, and at N in Fig. 2.

Referring now to Fig. 1, the operation of the control system is as follows: When the operator moves the switch M to position 1, the motor circuit is closed, including the resistances R', R², and R³ and the winding C' of the switch S'. This circuit may be traced as follows: from the positive through the series field F, the contact finger 5, the controller contacts, the contact finger 6, the motor armature A, the contact finger 7, the controller contacts, the contact finger 8, the resistance R', the switch winding C', and the resistances R² and R³ to the negative. If the motor current exceeds a predetermined value, the switch S' will remain open and when the current is reduced due to the speeding up of the motor, the switch will close but will not cause any of the resistance 70 to be cut out. When the operator moves his switch to position 2, the motor circuit goes from the contact finger 7 to the contact finger 9, and thence through the winding C² of the switch S², the contacts of the switch S', the winding C' and the resistances R² and R³ to the negative. The resistance R' is cut out, causing the current of the motor circuit to increase, and if the current exceeds the value at which the switch S² is adjusted to operate, it will remain open until the motor current has diminished, whereupon it will close its contacts. The current 80 no longer flows through the contacts of the switch S' and its winding C', but goes through the contacts of the switch S², the winding C³ and the resistance R³ to the negative. Since the winding C' is now de-energized the switch S' will drop open. The switch S³ will remain open, if the motor 85 current exceeds the value at which this switch is adjusted to operate, until the current has diminished, whereupon the switch will close, thereby cutting out the resistance R³. The motor circuit will then be as follows: from the positive through the series field F, the contact finger 5, the controller contacts, the contact finger 6, the motor armature A, the contact finger 7, the controller contacts, the contact finger 9, the winding C², the contacts of the switch S², the winding C³, and the contacts of the switch S³ to the negative. All of the starting 90 resistance has been cut out and the motor operates at its normal speed. 100

If the operator wishes to reduce the speed of the motor, he can move the switch M to position 1 thereupon cutting off the current through the windings and the contacts of the switches S^2 and S^3 and inserting the resistances R' , R^2 , and R^3 in the motor circuit. This circuit includes as before, the winding C' of the switch S' , and this switch will immediately close its contacts, but no resistance will be cut out until the operator 10 again moves his switch to position 2. To stop the motor, the operator's switch is moved to the central position as shown in the drawing, thereby opening the motor circuit.

If the operator's switch is moved to positions 3 and 4 the same operation will be obtained as that described for positions 1 and 2 except that the current is reversed in the motor armature thereby causing the motor to run in the opposite direction.

It will be noticed that the arrangement of the connections between the contacts and the windings of the switches S^2 and S' and between the winding of the switch C^2 and the operator's switch permits the circuit through the switch contacts to be opened to insert resistance while current is still flowing in the motor circuit without causing serious arcing at the switch contacts. This is an advantage since it is unnecessary to provide blow-out magnets and the necessary details for the contacts of the resistance switches.

In the system shown in Fig. 2, an additional bank or resistance R is used. When the operator's switch is moved to position 1, the motor circuit is closed including the resistances R , R^2 , and R^3 . This circuit does not include the winding C' of the switch S' and the switch S' , therefore, does not close as long as the operator's switch remains in position 1. When the operator's switch is moved to position 2, the current then flows through the resistance R' and the winding C' in a branch parallel to the resistance R and thence through the resistances R^2 and R^3 . If the current in the motor circuit exceeds a certain value the switch S' will remain open until the current has diminished, whereupon it will close its contacts and the motor circuit will then include the winding C^2 , the contact switch S' , the winding C' and the resistances R^2 and R^3 to the negative. The motor circuit through the contacts of the operator's switch can easily be traced. The closure of the switch S' cuts out the resistances R , and R' in parallel and the switch S' remains closed until the switch S^2 closes. This will occur when the current in the motor circuit is reduced to a predetermined value. When the switch S^2 closes, the resistance R^2 will be cut out, the winding C' will be deenergized, and the winding C^3 energized. The switch S' opens and the switch S^3 remains

open until the motor current is diminished, whereupon it will close its contacts and cut out the resistance R^3 . The motor is now connected across the line in a circuit including only the contacts and windings of the switches S^2 and S^3 . When the operator's switch is moved back to position 1, the circuit through the windings and contacts of the switches S^2 and S^3 is opened and the resistances R , R^2 and R^3 are inserted in the motor circuit causing the motor to run at a reduced speed. The switches do not open their contacts until after the circuit through them has been opened at the contacts of the operator's switch, and no arcing 70 75 80 at their contacts takes place.

On moving the operator's switch to positions 3 and 4 the same operation will take place as that described for positions 1 and 2 except that the current through the motor armature is reversed, causing the motor to run in the opposite direction.

It will be obvious to those skilled in the art that numerous changes can be made in the apparatus without departing from the 90 spirit of my invention.

I claim—

1. In a current-varying controller, a controlled circuit, a plurality of switches having contacts in the circuit, operating windings for the switches, means for connecting at least two of the windings in the controlled circuit at the will of the operator, means whereby the closure of the first switch energizes the winding of the second switch, and means controlled by the second switch for deenergizing the winding of the first switch.

2. In a current-varying controller, a controlled circuit, resistances for the circuit, a series of switches for cutting out the resistances, operating windings therefor arranged to be connected in the controlled circuit, means for causing the first switch to open when the second switch closes, and a contact in the circuit of the second switch winding closed at the will of the operator.

3. In a motor-control system, an electric motor, resistance for controlling the same, a series of switches having contacts for controlling the resistance, operating windings for the switches arranged to be connected in circuit with the motor, and means for connecting the motor in series with two parallel circuits, one of the parallel circuits including the contacts of one or more of the switches, and the second including the said resistance, the circuits being arranged, when the second switch of the series is closed, to cause the first switch of the series to open, 105 and means whereby the second parallel circuit is caused to be in circuit with the motor prior to the opening of the first parallel circuit.

4. The combination of resistance, switches 110 115 120 125 130

having operating windings and contacts adapted to be connected in the motor circuit, operator's contacts for connecting the winding of one switch in series with the resistance, operator's contacts for connecting the winding of the next succeeding switch in series with the first winding and in shunt with a part of the resistance, but only after the contacts of the first switch have closed, the contacts of the second switch when closed being arranged to cut out the first winding and another portion of the resistance.

5. In a motor control system, an electric motor, resistance for controlling the same, a series of switches for controlling the resistance, operating windings therefor successively energized by current through the motor, means whereby the second switch in closing causes the first switch to open, and

means for reinserting the resistance in the motor circuit when the second switch is closed.

6. In a motor control system, an electric motor, resistance for controlling the same, a series of switches for controlling the resistance, operating windings therefor successively energized by current through the motor, means whereby the second switch in closing causes the first switch to open, and so means for opening the circuit through the winding and contacts of the second switch and thereby leaving the said resistance in circuit with the motor.

Signed at Cleveland, Ohio, this 2nd day of Sept., 1913.

JAY H. HALE.
